WINDSHIELD ACCESSORY FOR A VELOCIPED

Viktor Schreckengost, Cleveland Heights, Ohio, assignor
to The Murray Ohio Manufacturing Co., Nashville,
Tenn., a corporation of Ohio

Filed Aug. 16, 1965, Ser. No. 86,593

Term of patent 14 years

(Cl. D34—15)

Fig. 3

FIGURE 1 is a perspective view of a windshield accessory for a velocipede showing my new design, a velocipede being shown in broken lines for illustrative purposes only;

I claim:

The ornamental design for a windshield accessory for a velocipede, substantially as shown and described.
